UNITED STATES PATENT OFFICE.

JESSE R. JEWELL, OF LINCOLN, NEBRASKA, ASSIGNOR TO NATIONAL MANUFACTURING COMPANY, OF LINCOLN, NEBRASKA, A CORPORATION OF NEBRASKA.

RELIEF MEANS FOR PRESSURE COOKERS.

Application filed June 25, 1921. Serial No. 480,481.

To all whom it may concern:

Be it known that I, JESSE R. JEWELL, a citizen of the United States, residing at Lincoln, in the county of Lancaster and State of Nebraska, have invented certain new and useful Improvements in Relief Means for Pressure Cookers, of which the following is a specification.

This invention relates to improvements in pressure cookers, and more particularly to means for relieving any excess pressure that might be built up within the cooker during its use, to eliminate danger of explosion, and the like, resulting from excess pressure therein.

Among the objects of my invention is to improve generally in the construction of covers for pressure cookers; further to provide improved means to permit the escape of steam, or the like, from within the cooker at such times as the pressure of the same exceeds a predetermined amount; further to provide an improved form of ball type safety valve for pressure cookers; further to produce an improved auxiliary release to function in the event the main safety valve becomes stuck, or for other reasons refuses to operate; further to provide a valve for pressure cookers that shall be positive in operation, easy of adjustment, accessible, and at the same time entirely fool proof; further to provide a valve that will be an absolute safe-guard against defective pressure gauges, and to reduce the cost of manufacturing, and the number of necessary auxiliary devices; further to provide pressure cooker relief means more simple, economical and efficacious than those heretofore known; and such further objects, advantages and capabilities as will later more fully appear.

My invention further resides in the combination, construction and arrangement of parts illustrated in the accompanying drawings, and while I have shown therein a preferred embodiment, I desire the same to be understood as illustrative only, and not as limiting the scope of my invention.

In the drawings:

Fig. 1 is an elevation of a pressure cooker embodying my invention.

Fig. 2 is an enlarged plan view looking down on Fig. 1.

Fig. 3 is an enlarged vertical section taken on line 3—3 of Fig. 2.

Fig. 4 is an elevation detail of my improved ball type safety valve.

Referring to the drawings, and more particularly Fig. 3, my improved ball type safety valve comprises the threaded base portion 1, secured by the threaded stem 2, to cover 3, for connection with the interior of the steam chamber of the pressure cooker. Extending through stem 2 and base member 1, is a longitudinal opening 4, terminating at its upper end in the steam cavities 5 and 6, forming primary valve seat 7, and secondary seat 8. Ball 9 rests firmly on primary seat 7, while a slight amount of clearance is provided between this ball and the secondary seat 8. Secured upon valve base 1, by threads, or the like, is the hood or casting 10, having an upwardly extending tubular portion 11 of smaller diameter, which at its upper end is internally threaded at 12 to receive nut 13', having a series of openings 14' for the reception of a wrench to rotate the same as desired.

Secured to and extending upwardly from ball 9 is stem 13 provided intermediate of its ends with flange 14, between which flange and the inner end of nut 13' is seated a coil spring 15, normally tending to hold ball 9 against primary seat 7. Formed in the hood 10 between the body portion thereof and the tubular portion 11, are a plurality of openings 16, through which steam, or the like, may escape from inside of the valve to the exterior. As will be readily understood nut 13' functions as an adjusting nut to adjust the tension of coil spring 15, as desired.

The operation of this valve is as follows: When the pressure within the cooker reaches a predetermined amount ball 9 is slightly lifted from primary seat 7, as the result of accumulated pressure in cavity 5, which is exerted against the lower face of ball 9. As soon as ball 9 is slightly raised, cavity 6 becomes filled with steam, and the much larger area enclosed by secondary seat 8 is exposed to steam pressure, whereupon the spring pressure is greatly overcome and the ball lifted much higher, thus allowing a full escape of steam through passage 4, cavities 5 and 6, and openings 16, in the valve cover.

or casing 10. As soon as sufficient steam has escaped, so that pressure in cavity 6 against the area of the ball exposed by secondary seat 8 is no longer sufficient to overcome the pressure of spring 15 from above, the ball is forced downwardly diminishing the flow of steam between the ball and the primary seat 7, which in turn further diminishes the steam pressure against the 10 large exposed area, causing the ball to return suddenly to primary seat 7. This results in a quick, positive and explosive opening of the valve when an excess pressure accumulates within the cooker, and an 15 abrupt sudden closing of the valve when the excess amount of pressure has been relieved.

It is of importance to note that the valve stem 13 is made integral with or secured to 20 the ball 9, and is provided with the spring seating flange 14, which is also integral with or firmly secured to this stem. Also that spring flange seat 14 slips readily into valve cover extension 11, and that stem 13 slips 25 readily through the opening in adjusting nut 13', both serving to guide and maintain the motion of ball 9, and stem 13 in a vertical direction, and after valve operation to always cause the same portions of the ball 30 surface to return to contact with seat 7. This insures an effective seating of the valve and eliminates danger of erratic action of the valve and leakage of steam because of irregularities on the surface of the ball.

35 Adjusting nut 13' may be set to any desired adjustment at the factory, and due to the requirement of a special kind of wrench to change this setting, such adjustment cannot be readily tampered with. This construction greatly facilitates the ready adjustment of the valve at the factory (and afterwards if the special wrench is provided), and eliminates such undesirable operations as grinding or clipping off ends of the spring, compressing or stretching the springs to lessen or increase the tension thereof, thus saving considerable time in the manufacture and adjustment of this form 45 of valve, and at the same time very materially increasing the efficiency of valve 50 operation.

55 Guiding stem 13 passing through adjusting nut 13' affords a ready means for manually lifting ball 9 from its seat, if desired, for the purpose of quickly releasing the steam pressure in the cooker, or the vacuum created therein, after the same has been allowed to cool. Said release of vacuum being necessary before the cover can be removed 60 from the cooker.

65 As will be noted the valve hood or casing 10, is secured to the base 1 by means of threads, as a result of which rotation of the hood or casing 10 will change the tension of coil spring 15 in accordance with the direction of

rotation. Referring to Fig. 4, it will be noted that an index mark 17 is provided on the exterior of base 1, and graduations 18 are formed on hood 10, these graduations bearing such relation to index mark 17 that 70 when they are caused to respectively register therewith, will indicate the corresponding gauge pressure within the cooker. For illustration, the parts as positioned in Fig. 4 indicate a gauge pressure in the cooker of twenty pounds per square inch, while if the hood be rotated to the right until mark indicated as fifteen registers with index mark 17, the setting of the spring will be such as to cause opening of the valve, when 75 the pressure within the cooker reaches fifteen pounds per square inch.

I have also provided an improved auxiliary means in the form of a secondary relief valve to function should the pressure within the cooker reach a point in excess of that 80 for which the ball valve is set, through the latter becoming stuck, or for other reasons, refusing to operate. This auxiliary or secondary relief means is indicated generally 85 at S in Fig. 3, the construction of which is as follows: An opening 20 of considerable size is provided in the top of the pressure cooker cover, the edges of which are bevelled 90 to form valve seat 21, to receive valve 22, having downwardly projecting stem 23, longitudinally slid able in an opening in cross bar 24. The upper face of valve 22 is provided with projection 25, over which is seated a coil spring 26, which is compressed 95 between the upper face of valve 22 and the under face of hood or casing 27, a sufficient amount to give desired resistance to valve 22. Screwed into suitable openings in cover 3 are upwardly projecting studs 28, formed 100 at their upper ends with a headed portion 29, adapted to pass through the enlarged opening 30, formed at the end of slot 31. From this it will be understood that in 105 applying hood or casing 27 spring 26 is first placed over projection 25 and hood 27 is then moved downwardly until heads 29 pass through enlarged openings 30 of bayonet slots 31, after which hood 27 will be rotated 110 to bring heads 29 to the rear of slots 31, which will thus hold hood 27 in position with spring 26, suitably compressed, and at the same time provide an escape for such steam 115 that may pass through valve 22 by way of openings 30 and 31. A suitable pressure indicator 32 will be mounted in cover 3 to indicate the pressure within the cooker.

120 From the above it will be understood that should ball safety valve 9 become stuck or refuse to operate, the pressure within the cooker as soon as it has exceeded that for which valve 9 is set will immediately lift valve 22 from its seat and effect a relief of the pressure within the cooker, thus eliminating all danger of explosion of the cooker 125

or other danger resulting from excess pressure therein.

Having now described my invention, I claim:

- 5 1. In a pressure cooker a cover, studs secured in said cover and extending upwardly therefrom, heads formed on said studs, a hood provided with bayonet slots adapted to receive the heads of said studs, 10 and a spring positioned between said hood and valve and compressed when said heads are passed through the enlarged portion of said bayonet slots and the hood rotated.
- 15 2. In a pressure cooker an auxiliary or secondary pressure relief means comprising a valve seat of considerable diameter formed in the cover, a valve on said seat, studs in said cover, heads on said studs, a spring bearing centrally on said valve, a hood having 20 bayonet slots adapted to receive the headed ends of said studs, so that when said ends are passed through said bayonet slots and the hood rotated, the spring will be held compressed between the hood and valve, and 25 means for guiding the movement of said valve in a rectilinear direction.
3. A relief valve comprising a body portion having a seat, a valve co-operable with the seat and having a guide stem, means co- 30 operable with the stem for guiding the movement of the valve and stem, a hood, means detachably connecting the hood to the body in spaced relation thereto for providing an escape opening between the hood and 35 the body, and a spring interposed between and pressing against the valve and the hood to normally hold the valve to its seat.
4. A relief valve comprising a body portion having a seat, a valve co-operable with the seat and having a guide stem, means co- 40 operable with the stem for guiding the movement of the valve and stem, a hood, studs detachably fastened to the body, said hood being detachably connected to the 45 studs and in spaced relation to the body for providing an escape space between the hood and the body, and a spring pressing against the valve to normally hold the valve to its seat.
- 50 5. A relief valve comprising a body por-
- tion having a seat, a valve co-operable with the seat and having a guide stem, means co-operable with the stem for guiding the movement of the valve and stem, a hood, means including pin and slot connections for detachably connecting the hood to the body whereby the hood may be quickly attached and detached, said hood being provided with a flange spaced from the body for providing an escape opening between the flange 55 and the body, and a spring pressing against the valve to normally hold the valve to its seat.
6. A relief valve comprising a body portion having a seat, a valve co-operable with the seat, means reacting against the hood and pressing against said valve for resiliently holding the valve to the seat, a hood for the valve, means connecting the hood to the body in spaced relation thereto for providing an escape opening between the hood and body, said means and hood cooperating to permit ready detachment of the hood without the removal of said means.
7. A relief valve comprising a body portion having a seat, a valve co-operable with the seat, means for resiliently pressing the valve to the seat, a hood for the valve, means connecting the hood to the body in spaced relation thereto and for providing an escape 60 opening between the hood and body, said means comprising studs detachably secured to the body and the hood, said hood being detachably connected to said studs without the removal of said studs.
8. A relief valve comprising a body portion having a seat, a valve co-operable with the seat, means for resiliently pressing the valve to the seat, a hood for the valve, means connecting the hood to the body in spaced 65 relation thereto and for providing an escape opening between the hood and body, said means comprising headed studs secured to the body and bayonet slots provided in the hood and co-operating with the heads of the 70 studs for detachable connection of the hood to the studs.
- 90 In witness whereof, I hereunto subscribe my name to this specification.

JESSE R. JEWELL.
